UNITED STATES PATENT OFFICE.

ALEXANDER NYMAN, OF NEW YORK, N. Y.

LOUD SPEAKER.

Application filed November 24, 1925. Serial No. 71,246.

My invention relates to improvements in sound reproducing devices; particularly electromagnetically operated loud speakers.

An object of this invention is to provide a 5 loud speaker adapted for use with radio receiving sets; capable of accurate adjustment and responsive to relatively weak currents; and characterized by very great sensitiveness and high efficiency in operation. 10 Other objects and advantages of my invention will be made clear from the following description and the novel features of my improvements are defined in the appended claims. But this disclosure is illustrative 15 only, and I may change the construction actually shown, in all matters relating merely to shape, size and arrangement of parts, without departing from the scope and spirit of the invention, as indicated by the broad 20 and general meanings of the terms in which the appended claims are expressed.

On the drawings,

Figure 1 is a side view partly in section of a loud speaker according to this invention; 25 Figure 2 is an end view thereof; Figure 3 is a side view of the support in which the parts of the loud speaker are mounted; Figures 4, 5 and 6 show details; and 30 Figure 7 presents curves showing the mode of operation of my invention.

The same numerals identify the same parts throughout. In the detailed description of the structure 35 shown, the numeral 1 indicates a vibratory diaphragm of metal or other suitable material, preferably corrugated; this diaphragm being connected to an armature 2 associated with an electromagnet 3, to cause movement of same. The diaphragm is located in a casing 4, the bottom of which is dished or provided with a recess 5; and upon the casing is a cap or closure 6, secured by fastening means such as screws 7. The rim of the cap 40 clamps the edge of the diaphragm against the edge of the casing, and in the recess 5 around the periphery thereof, may be an annular cushion, packing ring or gasket 8 against which the circumference of the dia-

45 phragm is firmly pressed. At the center of the cap is an outlet neck 9, to be connected to a trumpet or the like, to amplify the sound which the diaphragm creates.

From the outside or lower face of the bottom of the casing 4 projects a web 10, extending diametrically across the casing and being

at right angles to it. Into this web, from one side or edge thereof, runs a recess 11. The casing 4 can be cast in one piece with the web 10, or made in other ways. With the parts 60 in the positions illustrated, the upper and lower edges of the recess 11 are formed with notches 12 and 13, in line with each other, as in Figures 1 and 3. The web is not of very great thickness, as indicated in Figure 65 2, and along its lower edge it has opposite lateral flanges 14.

To cooperate with the electromagnet 3, I employ a permanent source of magnetic flux such as a pair of horse-shoe magnets 15; one 70 disposed against each face of the web 10; the limbs of the magnets being as far apart as the width of the recess 11. These magnets or magnetic elements 15 are permanent magnets and are held in place by clamps 16, each 75 magnet fitting more or less snugly between one of the flanges 14 and the bottom of the cap 4.

In the notch 12 and between the adjacent limbs of the magnets 15, I put a soft iron 80 pole 17. This pole piece 17 is clamped in position by the magnets 15, and it has lugs 18 at its outer or lower end to serve as bearings for a pivot pin 19 carrying the armature 2. This armature has two flanges 20 85 pierced for the pin 19; and is connected at one end to a rod 21, which runs to the middle of the diaphragm 1, through an opening 22 in the web 10. The ends of the rod 21 are riveted to both diaphragm and armature. 90

In the other notch 13 I put the core of the electromagnet 3. This core is U-shaped, made of laminations 23, and the magnet 3 is in line with the polepiece 17; and has its poles adjacent the armature 19. The core 23 95 bears two coils, the terminals of which are disposed on a piece of insulation 24, secured by screws to the edge of one flange 14, and against the side of the adjacent magnet 15. The terminals are in the form of ordinary 100 binding posts 26.

In operation the coils of the magnet 3 are joined to a radio receiving set, and upon signals arriving, the coil 3 will so affect the armature 2, as to rock it and vibrate the diaphragm 1. Normally, of course, the magnets 15 also attract the armature 2, the permanent magnetic flux acting through the polepiece 17 and laminations 23; but the armature is held motionless thereby and does not 105 begin to move till impulses of current traverse the coil of the magnet 3. 110

For purposes of adjustment, the portions 27 and 28 of the web 10 at the entrance to the recess 11 are perforated at 29 and 30 respectively; the latter perforation being threaded. 5 These perforations receive a threaded rod 31 having a screw head 32. When this rod is screwed in tight, it tends to draw the portions 27 and 28, and the limbs of the magnets 15 together; thus regulating the distance 10 between the armature 2 and the poles of the magnet 3.

By this construction I obtain a loud speaker which is very sensitive, and gives a maximum movement of the diaphragm for whatever 15 degree of force is momentarily exerted on the armature 2. In other words, what is generally known as a balanced condition between the tension of the diaphragm, and the force due to the magnets, is secured. For example, 20 let the abscissas in Figure 7 represent the forces that play a part in the operation of the diaphragm, and the ordinates represent the displacement or degree of movement of the diaphragm 1. Thus, if the line A is the 25 force due to the stress or tension of the diaphragm when moved or operated, and the line B is the force due to the magnetic flux which influences the diaphragm, this force being the resultant of the permanent mag- 30 netic flux of the magnets 15 and the temporary flux due to the impulses of current in the coil of the magnet 3, serving as means to vary the total flux; the force which actually causes the diaphragm to vibrate will be in- 35 dicated by the line C, plotted by subtracting the abscissas for instantaneous values of B from ordinates of corresponding values of A. From the shape of the line or curve C, one can see that a small increment or de- 40 crement of the unbalanced force acting on the diaphragm can cause a relatively large move- 45 ment of the latter. By means of the member 31, the loud speaker can be adjusted with extreme fineness and accuracy till the required operating conditions are found.

It will be clear from the above that whereas heretofore the magnetic balance in this type of loud speaker was obtained in a hit or miss manner of adjusting the air gap a 50 predetermined length to suit the strength of the magnet, I provide a positive adjusting means for the air gap. According to my invention a practical construction is obtained for securing the best possible magnetic bal- 55 ance on each manufactured unit of loud speakers.

Hence my improved loud speaker is very efficient and gives excellent results on even the weakest incoming oscillations.

60 Having described my invention, what I believe to be new and desire to secure and protect by Letters Patent of the United States is:—

65 1. A loud speaker comprising a sound pro- 125 ducing surface, a rocking armature con-

nected thereto, a source of magnetic flux, means for providing additional magnetic flux, and a member under tension for controlling the effect of said flux and said means in the actuation of said surface. 70

2. A loud speaker comprising a sound producing surface, a rocking armature connected thereto, a source of magnetic flux, means comprising an electro-magnet to provide additional magnetic flux, and a con- 75 trolling member under tension for said source and said means to adjust the operation of the loud speaker.

3. A loud speaker including a sound producing surface, a rocking armature connected thereto, a magnet to influence the armature, and a member under tension to adjust the relative positions of the magnet and the armature to control the operation of the loud speaker. 80 85

4. A loud speaker comprising a permanent magnet, an electromagnet with two adjacent poles of opposite polarity mounted thereon, a sound producing surface, a rocking armature connected to the surface and disposed adjacent said electromagnet, and a member to adjust the relative positions of the two poles of the electromagnet and the opposite pole of the permanent magnet. 90 95

5. A loud speaker comprising a permanent magnet, an electromagnet with two adjacent poles of opposite polarity mounted thereon, a sound producing surface, a rocking armature connected to said sound producing surface, and disposed adjacent to said electromagnet, a magnetic pole piece adjacent said armature, and a member to adjust the relative positions of said electromagnet and said magnetic pole piece and connected to draw said electromagnet and said pole piece toward each other. 100 105 110

6. A loud speaker comprising a permanent magnet, an electromagnet with two adjacent poles of opposite polarity adjacent a pole thereof, a rocking armature adjacent said electromagnet, a sound producing surface connected to the armature, and a member to control the distance between the limbs of the permanent magnet to regulate the operation of the loud speaker. 115

7. A loud speaker comprising a web having a recess, a magnet secured to the web with its limbs at the sides of the recess, a diaphragm, an armature connected to the diaphragm, and an adjusting member extending across said recess and operable to draw the limbs of the magnet towards each other. 120

8. A loud speaker comprising a web having a recess, a magnet having its limbs laid along the sides of the recess, a diaphragm, an armature connected to the diaphragm, a pole-piece adjacent one limb of the magnet, an electromagnet adjacent the other limb, and an adjusting member acting to draw said limbs toward each other. 125 130

9. A loud speaker comprising a diaphragm, a casing therefor, the casing having a web on its bottom, the web having a recess in one side and opposite flanges along its outer end, U-shaped magnets at each side of the web between the flanges and the casing, the limbs of the magnets extending along the sides of the recess, a polepiece set in a notch in the web between adjacent limbs of the permanent magnets, an electromagnet set in a similar notch in the web between the remaining limbs of said magnets, an armature between said electromagnet and said polepiece and connected to the diaphragm, and an adjusting device engaging the web across said recess to regulate the distance between the limbs of the permanent magnets. 40
10. A loud speaker comprising two magnets, and a web between said magnets, the web being shaped to receive a polepiece to cooperate with the magnets. 20
11. A loud speaker comprising two magnets, a web between said magnets, the web being shaped to receive the core of an electromagnet and an armature to be influenced by the electromagnet. 25
12. A loud speaker comprising a web, having an open-ended recess, a magnet on each face of the web, the limbs of the magnets extending along the edges of said recess, said 30
- edges each having a notch therein, and a pole-piece in one of said notches and a core in the other between said magnets. 35
13. A loud speaker comprising a web having a recess, a magnet secured to the web with its limbs at the sides of the recess, a diaphragm, an armature connected to the diaphragm, and an adjusting member engaging the web and extending across said recess to regulate the effect of said magnet. 40
14. A loud speaker comprising a web, a fixed magnet supported on said web, an electromagnet and cooperating polepieces supported on said web and an armature in operative relation to said electromagnet. 45
15. A sound producing device comprising a supporting web, one or more magnetic elements mounted thereon, an electromagnet supported on said web, and means for adjusting the magnetic action of said elements to 50 secure magnetic balance. 50
16. A sound producing device comprising a supporting web with magnetic elements mounted thereon, an electromagnet, a rocking armature and means for distorting said web to change the effect of said magnetic elements. 55

In testimony whereof I affix my signature.

ALEXANDER NYMAN.
